UNITED STATES PATENT OFFICE.

HERBERT H. DOW, OF MIDLAND, MICHIGAN, ASSIGNOR TO THE WESTINGHOUSE MACHINE COMPANY, A CORPORATION OF PENNSYLVANIA.

INTERNAL-COMBUSTION ENGINE.

No. 930,943.

Specification of Letters Patent.

Patented Aug. 10, 1909.

Application filed August 23, 1906. Serial No. 331,762.

To all whom it may concern:

Be it known that I, HERBERT H. Dow, a citizen of the United States, and a resident of Midland, in the county of Midland and 5 State of Michigan, have made a new and useful Invention in Internal-Combustion Engines, of which the following is a specification.

This invention relates to internal combustion engines in which improved means 10 are utilized for igniting the compressed charge in the engine cylinders.

The invention, broadly, consists in drawing a small portion of the partially compressed combustible mixture from the engine cylinder, compressing it to the point of ignition and discharging the burning gases into 15 the compressed charge in the gas engine cylinder and thereby igniting it.

20 The drawings accompanying this application and forming a part thereof are only illustrative, and I desire it to be understood that the invention may be carried out by other means or apparatus than those shown 25 or described, and I do not limit myself to any specific construction or to any form of apparatus.

Figure 1 is a partial section of a cylinder of an internal combustion engine provided with 30 apparatus for carrying out my invention. Figs. 2 and 3 are operating cams included in the apparatus illustrated in Fig. 1.

An engine cylinder 2 is provided with a piston 3, suitably valved discharge ports 4 35 and an admission port 5, which is provided with suitable valves (not shown). An auxiliary cylinder 6 is formed in the walls 7 of the engine cylinder and is provided with a piston 8, which is provided with packing 40 rings 9 or other suitable means for maintaining a fluid-tight working fit between it and the cylinder walls. A valve 10 controls the opening between the engine cylinder 2 and the cylinder 6 and is provided with a suitable 45 valve seat 11, arranged to insure a fluid-tight fit when the valve is closed. A valve stem 12 is rigidly secured to the valve 10 and extends centrally through the piston 8, suitable means being used for maintaining a fluid- 50 tight working fit. The end of the valve stem 12 is provided with a spring pocket 13, between which and a spring seat 14, formed integrally with the walls 7 of the cylinder, a helical spring 15 is located. The position of 55 the spring pocket 13 is rendered adjustable

along the valve stem 12 by means of a nut 16. The spring 15 operates to hold the valve 10 against its seat and thereby close the opening between the cylinders 6 and 2. A pivoted lever 17, which reciprocates the valve 10 60 through the agency of the valve stem 12, is provided at one end with a roller 18 which contacts with a cam 19. A pivoted lever 21 is connected at one end with the piston 8 and at the other is provided with a roller 22 65 which contacts with a cam 23. The cams 19 and 23, while shown on different lay shafts for the purpose of clearness, may be located on the same shaft and are driven at half the speed of the engine shaft by any suitable 70 means. The cam 19 has a cam surface 24, which moves the lever 17 to open the valve 10 and the cam 23 has a cam surface 25, which reciprocates the piston 8 in the cylinder 6. 75

The operation of the engine is as follows: As the piston 3 of the gas engine cylinder discharges the burned gases from the cylinder 2 the valve 10 is moved by the cam surface 24 to open the port between the cylinders 2 80 and 6 and which remains open until after the beginning of the compression stroke of the piston 3. The cam 23 permits the piston 8 to move to draw a fresh charge into the auxiliary cylinder 6 during the suction or admission stroke of the piston 3. After compression starts in the cylinder 2 the cam surface 24 of the cam 19 is moved to such a position 85 that the spring 15 operates to close the valve 10 and confine a partially compressed charge 90 in the cylinder 6. As soon as the valve 10 is closed, the cam surface 25 moves the piston 8 to compress the confined charge in the cylinder 6. The cam surface 25 is so arranged 95 that sufficient pressure is attained in the auxiliary cylinder 6 to fire the confined charge at about the time of maximum compression in the engine cylinder. The firing pressure in the cylinder 6 is sufficient to overcome the spring 15 and open the valve 10, thereby 100 discharging the burning gases into the compressed charge of the engine cylinder and igniting it. The piston 8 is held by the cam surface 25 in the forward part of the cylinder 6 until after the beginning of the suction 105 stroke of the piston 3 and then, while the admission valve of the engine and the valve 10 are still open, it moves back into the cylinder 6 and draws a portion of the fresh 110 charge from the gas engine cylinder 2. The

charge in the cylinder 6 is subjected to the increasing pressure of the engine cylinder 2 until the valve 10 is closed, and from that point compression is carried forward by the 5 downward movement of the piston 8.

While the spring 15 is designed to permit the valve 10 to open under the pressure occasioned by the explosion in the cylinder 6, it must be of sufficient strength to resist the 10 pressure in the cylinder 6 up to the point of ignition. Since the valve is subjected to high pressure on each side, the spring will only have to be strong enough to overcome the difference in pressure existing between 15 the cylinder 6 and the cylinder 2 before the explosion takes place in the cylinder 6. The time of ignition in the cylinder 6 can be adjusted by varying the position of the cam surface 25 or by varying the throw of the 20 piston 8. The tension of the spring 15 can be varied by changing the position of the spring pocket 13 by adjusting the nut 16.

It is apparent that this method of ignition may be used in various types of gas engines 25 and with gases with widely varying thermal values.

What I claim is:

1. In combination with a cylinder of a gas engine, an auxiliary cylinder communicating 30 therewith, an auxiliary piston located within said cylinder, a valve controlling communica-

cation between said cylinders, a cam for reciprocating said auxiliary piston to draw a portion of the compressed charge of the engine cylinder into the auxiliary cylinder and 35 to compress said charge to the point of ignition, a cam for reciprocating said valve to open and close communication between said cylinders, and means auxiliary to said cam for permitting said valve to open in response 40 to an expansion pressure within said cylinder.

2. In combination with a cylinder of a gas engine, an auxiliary cylinder communicating therewith, an auxiliary piston located within said cylinder, a valve controlling communication between said cylinders, means for reciprocating said piston to draw a portion of the compressed charge of the engine cylinder into said auxiliary cylinder and to compress said charge to the point of ignition, means 50 for reciprocating said valve to open and close communication between said cylinders, and yielding means for permitting said valve to open in response to an explosion pressure within said cylinder. 55

In testimony whereof, I have hereunto subscribed my name this eighteenth day of August, 1906.

HERBERT H. DOW.
